DISPENSING AND DISPLAY CABINET

Stanley T. Handel, New York, N. Y., assignor to
Eberhard Faber Pencil Company, a corpora-
tion of New York

Application April 1, 1935, Serial No. 14,028

2 Claims. (Cl. 312—42)

This invention relates to cabinets for storing and dispensing packages or articles, for example, small metal, wood or cardboard boxes containing leads for mechanical pencils, a prime object of the invention being to provide a cabinet of this character embodying novel and improved features of construction whereby the packages can be arranged in the cabinet so as to efficiently utilize the space in the cabinet and thereby permit a maximum number of packages to be stored in the cabinet, and at the same time permit easy access to the packages for individual removal thereof quickly by hand without disturbance or rearrangement of the packages.

Other objects are to provide such a cabinet which shall embody a novel construction including a plurality of removable storage units to contain stacks of articles or packages to be dispensed and each preferably having a discharge opening for individual removal of the articles or packages, said units being arranged in close and staggered or offset relation to each other without the use of partitions and so that the various units or packages exposed through said discharge openings can be grasped easily and quickly selectively and separately by the fingers of the store-keeper for removal of the desired packages from the cabinet; to provide such a cabinet which shall be simple and inexpensive; and to obtain other advantages and results as will be brought out by the following description.

Referring to the accompanying drawings in which corresponding and like parts are designated throughout the several views by the same reference characters,

Figure 1 is a perspective view partially in transverse vertical section of a cabinet embodying my invention, viewing the same from the rear.

Figure 2 is a transverse vertical sectional view on the line 2—2 of Figure 3.

Figure 3 is a horizontal sectional view on the line 3—3 of Figure 2.

Figure 4 is a detached perspective view of one of the containers for the individual packages.

Figures 5 and 6 are horizontal sectional views on the lines 5—5 and 6—6 respectively of Figure 4, and

Figure 7 is a detached perspective view of one of the spacer blocks.

Specifically describing the illustrated embodiment of the invention, the reference character A designates the body of the cabinet which has a rectangular compartment B to receive the storage units, packages or articles to be dispensed. This compartment is shown as formed with top and

bottom walls 1 and 2, side walls 3, and a front wall 4. The other or rear side of the compartment is open for insertion and removal of the storage units or articles into and from the cabinet.

The cabinet is especially designed for use with a plurality of storage units C in which are arranged in stacked relation a plurality of packages D each of which may contain a plurality of articles such as leads for mechanical pencils. The storage units C are shown as rectangular in shape and of a width and thickness corresponding to the length and width of the packages D, while the length of the units is such as to receive a plurality of the packages in stacked relation. As shown, the units are generally flat, that is, their thickness is much less than their width and length. Preferably, the storage units are identical in size, and each has a discharge opening 5 at one corner through which one of the packages D is exposed and may be removed.

The storage units C are arranged in the compartment B in substantially abutting side-by-side relation and edgewise with respect to the plane of the open end of the compartment, and alternate units are offset from adjacent units vertically with respect to the bottom of the compartment and horizontally relatively to the plane of said open side of the compartment or in general plane of the unit which is also parallel to the contiguous sides of the adjacent units, and the discharge openings 5 of the units are arranged at the bottom of the compartment B and facing the open side thereof. In this way, the packages in the various storage units are exposed through the discharge openings 5 of the respective storage units at the open side of the compartment B and the opposite sides of the lower-most package are freely accessible to be gripped by the fingers and permit the packages to be pulled from the discharge openings for dispensing.

The storage units C next adjacent the sides 3 of the compartment are spaced from said sides by spacer blocks 6 secured to the sides, while alternate units are spaced from the top and bottom 1 and 2 respectively of the compartment by spacer blocks 7. Similarly alternate units C are spaced from the front side 4 of the cabinet by spacer blocks 8. The spacer blocks 7 are of a width corresponding to the thickness of the storage units C and of a thickness sufficient to vertically offset the units to permit free access to the packages in the discharge openings 5. The spacer blocks 8 are of a width corresponding to the thickness of the storage units and of a thick-

ness to horizontally offset the units sufficiently to permit access to the packages. Also, it will be observed that each two adjacent spacer blocks 7 at the top and bottom of the compartment are spaced apart distances equal to the thickness of a unit C to receive a unit between them, and serve in conjunction with one spacer block 7, at the bottom and top respectively to form slide ways for the units C.

With such a construction, no partitions are required between the storage units, and consequently the storage space in the compartment may be efficiently utilized and the structure of the cabinet is simple. For holding the storage units in position, a keeper wire 9 may be separably secured to the blocks 6 and abuttingly engage the spacer units.

The packages or articles D will automatically fall by gravity in the storage units C so that as one package is removed, as shown at E, another package will descend into position to be removed from the discharge opening of the unit. The packages of the respective units can be selectively and individually manually removed without disturbing or rearranging any of the units or other packages, and the packages will be kept in orderly and easily accessible condition.

Preferably the storage units C serve as cartons or containers for packing and transportation of the packages D, and may be of folded cardboard construction as shown in Figure 4, although obviously the form of the storage units may be varied as desired. Also, other means may be utilized for maintaining the packages in stacked relation. The front wall 4 of the cabinet as well as the other walls may be suitably ornamented or contain advertising matter relating to the contents of the packages D, and if desired, a utility drawer 10 may be mounted at the top of the cabinet.

Other modifications and details of structure of the cabinet will be evident to those skilled in the art, and therefore I do not desire to be understood as limiting myself to the construction and use of the invention except as may be required by the following claims when construed in the light of the prior art.

Having thus described my invention, what I claim is:

1. A cabinet having a cubicle compartment formed with top, bottom, sides and one end wall, the other end being open, said cabinet being adapted to receive a plurality of identical rectangular storage units to contain articles to be dispensed, said units to be arranged in said compartment in abutting side-by-side relation and each of said units having a discharge opening at one corner to be disposed adjacent the bottom of the compartment and facing said open end and through which said articles are exposed and may be removed, spacer members on the sides of said compartment, spacer blocks on the top and bottom of said compartment in staggered relation spaced apart between said sides distances equal to the thickness of a unit and each of a width equal to the thickness of a unit and located to abut one end of a unit, and each two thereof to receive one unit between them, and other spacer blocks on the end of said compartment each in a common plane with one of the blocks on the bottom of the compartment, all of said spacer blocks being of a thickness sufficient to offset the respective storage units vertically and horizontally with respect to adjacent units in planes parallel to the planes of the contiguous sides of the units to permit said articles exposed through said discharge openings to be manually gripped selectively and separately for removal. 25

2. A cabinet of the character described having a rectangular compartment having an opening at one side whose plane is vertical, said compartment being adapted to receive a plurality of stacks of rectangular articles of the same size arranged in said compartment in close substantially abutting side-by-side relation, and means on the bottom and the wall of said compartment opposite said open side for locating said stacks with alternate stacks offset horizontally from adjacent stacks relatively to the plane of said open side and vertically with respect to the bottom of the compartment to permit said articles at the bottoms of the stacks to be freely gripped for removal of the articles. 45

STANLEY T. HANDEL.
